UNITED STATES PATENT OFFICE.

BURNHAM C. STICKNEY, OF ELIZABETH, NEW JERSEY, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,183,826.

Specification of Letters Patent.

Patented May 16, 1916.

Continuation of application Serial No. 668,822, filed January 2, 1912. This application filed June 26, 1912, Serial No. 705,899. Renewed April 17, 1916. Serial No. 91,517.

To all whom it may concern:

Be it known that I, BURNHAM C. STICKNEY, a citizen of the United States, residing in Elizabeth, in the county of Union and State of New Jersey, have invented certain new and useful Improvements in Combined Type-Writing and Computing Machines, of which the following is a specification.

This invention relates to combined type-writing and computing machines of the Underwood-Hanson type, in which computation pins are set up by the numeral keys of the typewriter, and subsequently employed for the purpose of determining the extent of rotation of the dial wheels of the computing mechanism, and is a continuation of my application No. 668,822, filed January 2, 1912. Such a machine is illustrated in United States Hanson Patent No. 905,421, dated December 1, 1908, and pending application of F. A. Hart, No. 466,836, filed December 10, 1908.

The object of the present invention is to improve the computing mechanism in this general class of machines, with a view to providing a simple mechanism to adapt the machine to effect both addition and subtraction according to the British monetary standard; although certain features of the improvements may be used in machines adapted for other standards, especially certain features of the subtracting mechanism.

In machines of the Underwood-Hanson type, the key-set computation or index pins are arranged upon racks or rack-bars, which mesh with pinions connected to the dial wheels, and said pins are employed for the purpose of determining the extents to which the dial wheels are driven.

One of the dial wheels employed in computing British money is the pence wheel, which is a double wheel, one part being reserved for units, and the other part for tens; this wheel being designed to make twelve steps for each revolution, as there are twelve pence in a shilling.

In order to make it practicable to employ the usual numeral key "1" in computing in both the tens and units places in the pence column, I provide three of the computation-pin racks or bars to be used in association with said pence wheel. The first of these

bars is used only for computing tens, the second only for computing from two to nine pence, and the third only for computing a single penny. The first computing-pin bar has no rack teeth, but drives the second computing-pin bar, which has a rack to mesh with the pinion on the pence wheel. The third of these racks, namely the one for computing a single penny, has a rack in mesh with a pinion provided upon a special computation wheel which has no dial, but which is adjacent to the pence wheel, and is provided with a carry-over train which operates every time that the special wheel is operated. The second and third racks are connected to be simultaneously brought into position to have their pins set by the keys.

It will be understood that if only two racks were employed, and if the second or units rack should have a "1" computation-pin thereon, and if the numeral key "1" should be employed to write eleven pence, the ten-pence pin and the one-penny pin would both be set, but the pence wheel would thereupon be advanced only ten points, as this setting of the one-penny pin would be nugatory, since the units rack is driven ten points by the ten-pence bar. But by having a third rack, which is not driven by said ten-pence bar, but is independently driven, a pin can be set upon said third bar by said numeral key, and said special wheel can be rotated one point thereby, and such rotation in each case starts in action the carry-over train, so that 1 is carried on to the pence wheel after the latter is turned the ten points, thus making eleven pence.

The farthings wheel is provided with a carry-over train which carries 1 directly onto the pence wheel. Moreover said special or dummy wheel, at each step, of course, causes 1 to be carried over on to the same pence wheel. The latter may be operated by either train independently of the other train. All of the wheels and carry-over trains are turned backwardly to effect subtraction. Any suitable means may be employed for reversing the direction of rotation of the dial wheels. There is illustrated a double rack which may be set either up or down to add or subtract, as the case may be, at the forward stroke of the general opera-

tor. Preferably this double rack is normally out of mesh, but is thrown into mesh as the general operator starts, and is again thrown out of mesh as the general operator completes its forward movement, so that the rack can return to normal position without turning its pinion, which in each case is fastened to the dial wheel. The carry-over mechanism includes a shaft which carries spurs to drive the pinions in the carry-over trains; and this shaft in the present instance carries two sets of spurs, and is reversible or capable of being rotated in either direction from normal position, thus bringing either one set or the other into play to cause the carry-over trains to add or subtract. A single lever adjusts the clutching mechanism for controlling the direction of movement of the spur-carrying shaft, and for determining whether said racks shall be thrown up or down, and hence whether the dial wheels shall be advanced or reversed. There is also provided means for preventing more than nineteen shillings being written on the work sheet, and also for preventing the writing or more than eleven pence or more than three farthings.

Another feature of this convention consists in the provision of means for returning all the dial wheels to zero. An arbor extends through all the dial wheels, and fixed thereon are certain collars which have pockets containing balls and springs; and the corresponding dial wheels have recesses into which the balls are pressed by the springs, thus forming the clutching connections between said arbor and said dial wheels. For certain of the wheels, as for instance the tens of shillings wheel and the farthings wheel, there are provided loose collars on said arbor, which remain motionless during part of the rotation of the arbor, and are finally moved thereby only very short distances, as it is necessary to turn said wheels only through very short arcs in order to bring them to the required positions. The farthings wheel, however, is rotatable by said arbor through four points, so that it starts its carry-over train. All of these functions are performed during the forward stroke of the general operator; and during the return stroke thereof, all of the carry-over trains are operated one after another, to bring all the wheels to zero; said arbor having originally turned the higher wheels each to within one point of zero.

In order to enable the machine to subtract, there is connected to said subtraction handle or lever a device which silences the zeroizing clutches aforesaid, thus permitting the dial wheels to be turned backwardly upon said arbor. The zero key is also provided with means for setting the machine from subtraction to addition, so that it is

insured that said clutches shall become effective, and thus enable the zero-setting mechanism to operate.

Other features and advantages will hereinafter appear.

In the accompanying drawings, Figure 1 is a side elevation of a combined type-writing and computing machine of the Underwood-Hanson type, showing the present improvements applied thereto; the parts being in normal positions. Fig. 2 is a plan of the dog and jack mechanism usually employed in connection with the typewriter carriage for displacing the computation bars one after another, so that the pins may be set thereon. Fig. 3 is a sectional plan of the base of the machine. Fig. 4 is a part sectional plan of the principal computing devices. Fig. 4^a is a detail of the means for carrying over from the farthings dial wheel to the pence dial wheel. Fig. 5 is a sectional front elevation taken through the computing wheels and computation racks; the parts being in normal positions. Fig. 6 is a perspective rear view of the shiftable mechanism for controlling the addition and subtraction operations; the parts being shown as shifted to subtraction position. Fig. 7 is a sectional side elevation showing the farthings dial wheel and its carry-over train, all in normal positions. Fig. 8 is a similar view, showing the carry-over train started by means of a tooth on the dial wheel. Fig. 9 is a sectional side elevation of the tens of shillings dial wheel. Fig. 10 is a perspective view of one of the carry-over trains. Figs. 11 to 21 are diagrams of the double set of addition and subtraction spurs. Fig. 22 is a sectional side elevation, showing a dial wheel, a carry-over train, and the set of spurs seen at Figs. 11 to 21. Fig. 23 is a sectional side elevation, illustrating the beginning of the movement of the general operator whereby the racks are shifted to position for subtraction, and before the advance of the cross bar which carries forward the computation racks. Fig. 24 is a similar view, but showing the forward strokes of the parts completed. Fig. 25 is a sectional side elevation of the mechanism contained in the base of the machine. Fig. 26 is a sectional side elevation of a computation bar having a single computation pin for computing ten pence. Fig. 26^a is an elevation of the rear portion of the tens of shilling computation bar. Fig. 27 is a sectional side elevation of the one penny bar, together with the auxiliary computing pin operable thereby, and its carry-over train. Fig. 27^a shows the rear portion of the farthings computation bar. Fig. 28 is similar to Fig. 27, but shows the computation mechanism for "2" to "9" pence. Fig. 29 is a sectional side elevation, showing the mechanism for computing in pounds, and also showing the sub-

traction and addition controlling devices, and a portion of the general operator. Fig. 30 is a sectional side elevation, showing some of the parts of the zero setting mechanism, and also a portion of the device for setting the computation racks to addition and subtraction positions. Fig. 30^a is a sectional side elevation taken through the key-operated linkages and associated parts. Fig. 31 is a sectional plan of the clutch mechanism which is employed for shifting the driver of the spur trains of the carry-over mechanism from addition to subtraction. Fig. 32 is a sectional front elevation, illustrating the normal position of a device which locks the machine against printing more than eleven pence. Fig. 33 is a similar view, showing the locking parts as moved idly from the Fig. 32 position at the elevation of the ten-pence computing bar. Fig. 34 is a sectional elevation of the clutch pinion which operates the general spur-shaft of the carry-over mechanism. Fig. 35 shows the Fig. 32 device as moved to effective position. Fig. 36 illustrates the action of the farthings computation bar in illustrating the locking device of Fig. 32 to normal position. Fig. 37 is a sectional side elevation of the farthings wheel and the totalizing arbor, showing the parts in normal positions. Fig. 38 is a similar view, showing the arbor as having rotated two-thirds of a revolution idly as respects said wheel. Fig. 39 is a similar view illustrating the return movements of the parts. Fig. 40 is a similar view, and shows the completion of the operation from the Fig. 38 position. Fig. 41 is a sectional rear elevation of the key operated linkages, the computation bars and pins thereon and the carriage operated linkages for displacing said bars. Fig. 42 is a perspective front view of a double linkage, which is operated by the "1" numeral key. Fig. 43 is a perspective rear view of the arbor whereon the computation wheels are mounted whereby said wheels are turned to zero. Fig. 44 is a plan of the portion of the casing which has the sight holes through which the numbers on the wheels are viewed; there being four openings, one for each set of wheels, pounds, shillings, pence and farthings. Fig. 45 is a sectional elevation to show the farthings carry-over train as having been started by the starting tooth on the farthings dial wheel, and in position to operate the pence dial wheel on the return stroke of the general operator; said pence dial wheel being operable independently by either the farthings carry-over train, or the carry-over train which extends from the dummy or "blind" wheel to the pence dial wheel.

In said machine, alphabet keys 1 and numeral keys 2 depress lever 3 and to operate bell cranks 4, to swing type-bars 5 up to

strike against the front of a platen 6, which is mounted on a carriage 7, propelled by a spring barrel 8 and controlled by an escape-wheel 9 and dogs 10, the latter operated by a universal bar 11 mounted on a reciprocating frame 12, which is carried at its rear end by idle links 13; said universal bar being operated by heels 14 on the type bars. Said numeral keys have stems 15 to depress arms 16 on rock shafts 17, which form parts 70 of linkages 18; said linkages also including horizontal depressible bars 19, which extend horizontally across the machine to enable the keys to depress any of a nest of computation pins 20. Said pins 20 are carried upon bars 75 21, which operate the dial wheels; there being at least one bar 21 for each denomination.

The carriage of the typewriter selects or determines the denomination in which computing is to be done upon the depression of any numeral key. For this purpose, the carriage carries a dog 22 to engage and cam up or lift any of a series of jacks 23, which are pivoted at 24, and at their rear ends depress rods 25, the latter connected by levers 26 to linkages 27 which lift the rear ends of the bars 21; each jack 23 being connected with its own bar 21, so that the position of the carriage 7 determines which one of said bars 90 21 shall lie in elevated position at the depression of any numeral key 2. At their forward ends, the bars 21 have racks 28 to engage pinions 29, which are fixed to their respective dial wheels 30.

The actuation of the rack bars 21 is the same as heretofore; the general operator being driven by a crank 31 or otherwise, and comprising a pair of racks 32, to which a preferably hollow shaft 33 is connected by segments 34 fixed on said shaft, idle pinions 35 intervening between said segments and said racks 32. The racks are connected by back and front horizontal bars 36, 37. The bar 36, as usual, engages any of the pins 20 110 which have been depressed by the keys; and accordingly the racks are driven forward and the computing wheels rotated. The return movement of the general operator may be caused or assisted by a spring 38, Fig. 1; 115 and the cross bar 37 of the general operator may engage lugs 39 pendent from the bars 21, to drive the latter backward to normal positions; all the dial wheels remaining motionless while this is done, being held by spring detents 40. Also carried upon the forward end of each bar 21 is a rack 41 to be used for subtraction; this rack parallel with the rack 28 and overlying the pinion 29, but adapted to drop into engagement with said pinion, so as to turn the pinion in reverse direction at the forward stroke of the bar 21 effected by the forward stroke of the general operator bar 36. The racks may be connected in any suitable way as for instance 120 125 130

by means of a yoke 42, which may be integral with the racks.

Both racks 28 and 41 stand normally out of engagement with the dial-wheel pinion 29. At the start of the general operating handle 31, the rack 28 may be swung up into engagement with said pinion. For this purpose, there is provided a cam 43, to engage a pin or roller 44 on an arm 45 which extends back from a horizontal transverse rock shaft or stud 46; an arm 47 extending forwardly from said stud, and forming one of a pair of arms which carry at their forward ends a shifting and guiding bar 48, which passes through slots 49 in said racks 28; said slots extending horizontally and being about equal in length to the racks themselves. The other arm 47 of said pair, is pivoted upon a stud 46^a in line with the stud 46. The arms 47 may also be rigidly connected by a shaft 46^b fixed in ears 46^c formed on said arms. Continued motion of the handle 31 in forward direction causes the general operator 32 to advance, and the bar 36 thereon to engage the depressed pins 20 to advance the racks 28 and rotate the pinions 29 and dial wheels 30 for addition.

It will be seen that the connection between the handle 31 and the cam 43 is such as to permit a rotative movement of the cam 43 about the axis 33, in advance of the rotation of the segment 34, which is positively connected to the general operator 32. Said handle or crank 31 is fixed upon a driving shaft 35 or axle 50, which extends loosely through the hollow shaft 33 that rigidly connects the segments 34, so that the handle may be started ahead of the starting of said hollow shaft and general operator. This advance starting movement of the handle is used for depressing the pin 44 by means of the cam 43. Said cam is in the form of a pawl which is pivoted at 51 to an arm 52, which projects from a sleeve 53 which is loosely mounted upon said hollow shaft 33, and the pawl has a foot 54 to rest on said sleeve 53, and is pressed toward said sleeve by a spring 55, Fig. 6.

A bit or key 56 projects from the crank 50 axle 50 into a slot 57 in said sleeve 53, whereby the latter is caused always to turn with the crank. It will be seen that said bit 56 extends through a slot or opening 58 in the intermediate hollow shaft 33, said slot 58 extending partly around the axle 50 to permit limited vibration of said axle while the hollow shaft 33 and the general operator 32 remain stationary, whereby the cam 43 is enabled to act, and all the racks 28 are lifted into engagement with the pinions, before said racks begin to be advanced by the general operator 32. By the advancement of said racks, the dial wheels are turned to various extents determined by the pins 20 that have been set.

It will be seen that the cam 43 merges into a curved edge 59 which is concentric to the axle 50, and that the roller or pin 44 is maintained motionless in its depressed position until the forward stroke of the general operator 32 is practically completed, so that the racks 28 are held in mesh with the pinions 29 during said forward stroke of the general operator. At the final portion of said forward stroke, the pin or roller 44 drops off from the end of the edge 59, and the parts 45, 47, 48 are returned to normal positions by spring 60, to permit the racks to be driven back to normal position while the pinions 29 remain motionless.

There may be two springs 60, one at each end of the rack controlling frame 46^b, 47, 48. Said springs coil around stems 61, which are guided horizontally in brackets 62, and carry at their forward ends heads 63 to engage double cams 64, the latter having hubs 65 fixed to the arms 47, and turning upon the studs 46, 46^a, Figs. 3 and 6. The cams 64, in each instance, are placed one below and one above the pivot 46 or 46^a, so that the springs 60 may return the racks to midway normal positions after they have been either elevated or depressed into engagement with the pinions. The pin 44 having snapped off from the high or dwell portion 59 of the cam, and the spring 60 having restored the rack-shifting frame to its normal or midway position, the crank 31 is now pushed back to normal position. During this operation, the drive axle turns 100 backwardly, and the hollow shaft and sleeve are also turned backwardly by the bit 56; the cam member or pawl 43, 59 yields upon its pivot 51 to permit it to slip past the pin or roller 44; and the spring 55 snaps 105 the pawl again toward the sleeve 53 with its foot 54 resting upon said sleeve; said foot being placed at one side of the pawl so as to give clearance to the pin or roll 44.

The setting of the machine frame for subtraction involves shifting of the cam-carrying sleeve 53 endwise along the hollow shaft 33 to the Fig. 6 position, to silence the cam 43 by shifting it out of its position, so that it cannot engage the wrist 44. At the same 115 time, an oppositely placed cam 67 on the other end of the sleeve 53 is shifted into position to engage a pin or roll 68 carried upon an arm 69 at the other side of the shifting frame from the arm 45. Arm 69 120 is adapted to be raised by said cam 67 during the starting of the handle 31, so as to depress the arms 47 and shifter bar 48, and bring the top racks 41 down into mesh with the computation pinions 29, so that the latter may turn backwardly during the forward stroke of the general operator 32, during which time the roll 68 runs upon a curved edge 70 concentric with the axle 50, to hold the racks in mesh with the pinions. 130

At the conclusion of the stroke, the pin 68 drops off from the end of the cam pawl 67, 70, permitting springs 60 to lift the racks to normal midway positions in advance of 5 the return of the racks effected by the general operator 32 at the return stroke of the handle 31. During such return stroke, the cam pawl 67, 70, rides past the projection 68, and is snapped into normal position by 10 a spring 71 with its foot 72, (Fig. 30) resting upon the sleeve 53. Thus it will be seen that the racks mesh with the pinions only during their initial strokes, and are out of mesh with the pinions during their 15 return strokes. It will be understood, however, that this construction of racks and pinions and shifting devices may be employed in connection with other forms of tens-carrying mechanism that the form hereinafter 20 described; it will also be understood that the described tens-carrying or carry-over mechanism may be used in connection with other means for advancing and reversing the dial wheels or computation wheels or 25 pins.

The mechanism may be set for subtraction by means of a handle 73 (Figs. 1 and 6) rising from a horizontal rock shaft 74 extending rearwardly; the rear end of said 30 rock shaft having a pendent arm 75 connected by a link 76 and collar 77 to said sleeve 53; a pin 78 projecting from said sleeve through a circumferential slot 79 in said collar, to insure the sleeve traveling 35 with the collar while accommodating the independent rotative movement of the sleeve. A spring detent 80 may engage one of two notches 81, 82, in an arm 83 fixed on said rock shaft to hold the parts in either 40 addition or subtraction shift positions. The slot 57 in the sleeve 53 is long enough to accommodate the shifting movement thereof, Fig. 6.

The hereinbefore described features are 45 applicable to machines for general computation, and for computing according to United States money; and the same is true of some of the features hereinafter to be described; but certain features of the present invention are especially applicable to a machine for computing according to the British monetary standard. In Fig. 4 all of those dial wheels which have ten digits marked thereon are marked 30; and it will 50 be seen that these include seven wheels for adding pounds, and one wheel for adding units of shillings. All of the remaining wheels and their driving racks are special.

The dial wheel for tens of shillings is 55 designed as 84, and is intended to be read in connection with the units shillings wheel; this pair of wheels being separated by a space 85 from the pounds group, and by a space 86 from the pence group. The 60 periphery of the wheel 84 has five divisions,

each carrying the numeral "1" and a blank or zero space. It has five teeth 87 for starting the carry-over operation; each of the wheels 30 having only one starting tooth, (except the wheel 30 at the extreme left-hand end of the pounds group, which has no starting tooth, as it is never operated except by the tens-carrying mechanism which connects it to the wheel of next 70 lower denomination). The machine is constructed to carry over or transfer from the units shillings wheel to the tens shillings wheel 84, at each complete revolution of the former; and to carry over one to the units of pounds wheel 30 five times during each 80 revolution of the tens of shillings wheel 84; or in other words, every second advance movement of the wheel 84 starts the carry-over train to operate the lowest pound wheel.

The dial wheels for tens of pence and 85 units of pence are rigidly connected together, forming a double wheel, which is designated as 88. The dial wheel for the units of pence is provided with twelve parts, bearing the digits "0," "1," "2," "3," "4," 90 "5," "6," "7," "8," "9," "0," and "1." The last two digits are read in connection with the two characters "1," "1," which show on the ten pence dial wheel, thereby designating ten pence and eleven pence. The pence wheel 88 is designed to have twelve steps in one entire revolution; and once in each revolution a starting tooth 87 thereon initiates the movement of the train which carries over 1 onto the units of shillings wheel 95 30. There is also provided a farthings dial wheel 89, Fig. 4, which is designed to be capable of twelve individual movements in each revolution, and has three starting teeth 87, and bears the digits "0," "1," "2," 100 "3," "0," "1," "2," "3," "0," "1," "2," and "3"; and three times in each revolution the 105 train is started for carrying over one on to the pence wheel 88.

Each of the rack-bars 21 which operate 110 the pounds wheel, Fig. 4, carries nine of the key-set pins 20; and there are nine corresponding linkages 18; said linkages being also adapted to operate the pins on other bars. The rack-bar 21 for operating the 115 units of shillings wheel has also nine of these pins 20.

The rack-bar which operates the tens of shillings wheel 84 is special, and is designated as 90, and carries only one pin 20, 120 which is a "1" pin, as said bar 90 never advances more than one point, since the wheel 84 never turns but one step at a time.

There are provided three bars for operating the pence wheel 88. The first of these 125 bars is designated as 91 and has a single key-set pin 92 and is intended only for advancing said pence wheel ten points. The pin 92 is intended to be set by the usual numerical type-key connected to the type 130

“1,” but only when the typewriter carriage 7 stands in position for writing “1” in the tens of pence place on the work sheet; and this, of course, is the only time in which 5 the bar 91 can be elevated by dog 22 and its connections. The pin 92 is placed in rear of all the pins 20, so that said pin 92 may be caught by the advancing cross-bar 36 in advance of any of the pins 20, and 10 hence the bar 91 may be given a correspondingly longer stroke. This pin 92 is depressible by a special linkage 93, which is operated by a special arm 94 which is fixed to the first rock shaft 17, Fig. 4, the arm 16 15 of which is depressed by the numeral key “1.” This linkage 93, of course, operates every time that the numeral key “1” is depressed; but it usually moves idly, and becomes effective only when the bar 91 is 20 elevated through the means of the carriage dog 22. The bar 91 need not have any rack teeth, but instead thereof, may be provided with a lug 95 to engage a shoulder 96 on a rack bar 97, which directly engages a pinion 25 97^a on the pence wheel; so that when the bar 91 is carried forward, the rack bar 97 goes with it and turns the pence wheel 88 ten points.

Upon the return stroke of the general operator, the bar 37 engages the lug 39 upon rack bar 97, and returns said rack-bar together with the bar 91. Thus it will be seen that bar 91 is free to be lifted independently of the rack bar 97, so as to permit the 30 setting of the pin 92, while said bar 91 cannot be advanced without advancing the rack bar 97 and driving the wheel 88, and bar 97 cannot be retracted without carrying back the bar 91. At Fig. 26, it will be seen that 35 bar 91 has a slot 49 supporting the forward end of said bar on the rod 48. The forward end of the bar 91 therefore swings up and down idly when the rod 48 shifts. The rack-bar 97, Figs. 4 and 28, having the 40 racks for operating the pence wheel, is provided with key set pins, and may be advanced independently of the bar 91, although, of course, this does not happen whenever the number of pence to be added 45 or subtracted exceeds “nine”.

The general construction of the units of pence rack-bar 97 is similar to that of the rack bars 21, but it has no pin for “1”; only eight pins from “2” to “9” being 50 shown. The “1” pin is omitted from the bar 97, and other provisions are made for adding or subtracting a single penny, for the reason that if the linkage 18, which is connected to the “1” key, were to depress 55 a “1” pin on the rack bar 97, after the pin 92 had been depressed, with the idea of writing and adding “11”, it would happen that at the ensuing movement of the general operator the rack bar 97 would be advanced 60 by the lug 95 only ten points; and hence the

setting of the “1” pin on said bar would be rendered wholly nugatory.

A special rack-bar 98 is provided for carrying a single “1” pin 99, for adding a single penny, Figs. 4 and 27; this being the 70 third of the three bars which are associated with the pence wheel. Said rack-bar 98 is not provided with any linkage 27, but has a projection 100 which overlies a lug 101, Figs. 4, 27 and 28, on the units of pence 75 rack-bar 97, so that whenever the latter is lifted by the carriage dog 22, the rack-bar 98 is also lifted, and hence the penny pin 99 may be depressed by that linkage 18 which is connected to the numeral key “1”. Thus 80 it will be seen that upon depressing the numeral key “1” twice, for writing eleven pence, the first stroke of said key sets the pin 92, by means of linkage 93, while the second stroke of said key does not affect any 85 pin on bar 97, but does set the pin 99 on bar 98. This bar 98, when subsequently driven forward by the general operator, sets in motion means for either adding or subtracting one penny upon the pence wheel 90 88, wholly independently of the operation of said wheel 88 by means of the “10” pin 92; so that “11” is either added or subtracted on said wheel, as the case may be.

As will be seen at Fig. 27, the bar 98 95 (which in this respect is like the rack-bar 90), has short addition and subtraction racks 102, 103, as a movement of only one step is intended to be imparted thereby; thus initiating a movement whereby 1 is carried by the carrying-over train on to the pence wheel 88, this carrying-over operation occurring during the return movement of the general operator 32 (as will presently be explained) and hence occurring after the 100 pence wheel 88 has been turned ten points by the coöperation of the bars 97 and 91; so that the rotation of said wheel 88 ten points by said bars 97 and 91 does not prevent the addition of the penny which is written in 105 the units place of the work sheet. Since the provision is made on the separate bar 98 for the units key-set pin 99, it follows that bar 98 must always be used for adding or subtracting a single penny, and hence no “1” 110 pin is provided upon the bar 97, and the bar 98 is movable forwardly and backwardly independently of the bar 97, so that wheel 104 may be operated by the bar 98, while the bars 97 and 91 remain motionless; a penny 115 subsequently being carried over on to the wheel 88 in a manner presently to be explained. The last rack bar 105 in the system, carries only three pins 20, for one, two and three farthings; and the racks on the 120 front of said bar may be shortened accordingly, as they never turn the farthing wheel 89 more than three points or steps at a time.

The tens-carrying or carry-over mechanism, employed in this machine is shown 125 13

in section at Figs. 7 to 22. It comprises a series of trains, each of which is started by the tooth 87 on the associated dial or computing wheel, one of which is seen at Fig. 22. This starting tooth 87 engages and drives a nine-tooth pinion 106, giving the latter one-ninth of a revolution; the tooth 87 at the completion of this stroke moving out of engagement with said pinion 106, as seen in dotted lines at Fig. 22. Fixed to said pinion 106 is a mutilated pinion 107, similar to pinion 106, but having every third tooth removed. Normally each mutilated pinion 107 (of which there is one in every carry-over train) stands in such position that it affords a clearance for its associated driving spur or spurs, these spurs being designated as 108, and there being one of them for every pinion 107. In operating the machine for addition, the rotation of the two pinions 106, 107 effected by the starting tooth 87, in passing from the full-line to the dotted-line position at Fig. 22, moves a tooth of mutilated pinion 107 up in the path of its associated driving spur 108; and when the latter swings upwardly, the pinions 106, 107 are revolved together. A three-toothed wheel 109, fixed to pinion 106 and 107, meshes with a gear 110 upon the next computing wheel above. By means of the tooth 87 and the spur 108, the three-toothed pinion 109 is turned through a third of a revolution, and one of its teeth swings into and out of mesh with said gear 110, moving the same one step, or the distance from one tooth to the next; usually one-tenth of a revolution, but in some cases one-twelfth of a revolution.

The spurs 108 are fixed upon a power-driven shaft 111. The axes of the dial wheels 30, the pinions 106 and 107 and 108, and the shaft 111, are preferably in the same plane, as illustrated in Fig. 22; but by raising the shaft on which said pinions are mounted, it will be possible if desired to make the teeth of pinions 107 register with the teeth of pinions 106, as illustrated in the United States patent to Hanson, No. 905,421, whereas with the present arrangement the teeth are staggered. Spring detents 112, Figs. 1 and 25, engage the teeth of pinions 106 to hold them against accidental rotation; these detents being connected by springs 113 to the above-mentioned detents 40.

The spur-carrying shaft 111, is connected to be driven by the general operator. For this purpose a pinion 114, Figs. 1 and 29, meshes with the general operator rack 32, and transmits power to a pinion 115, mounted on said shaft 111, and connected to be able to turn the same. This pinion 115, Figs. 31 and 34, rotates idly during the forward stroke of the general operator; said pinion having a clutch connection with

the shaft, comprising a ball 116 and spring 117, both confined in a pocket 118 in a hub or collar 119 (Fig. 34) on which said pinion is loosely mounted; the pinion having a pocket 120 to receive said ball to form a connection between said pinion and said hub 119, and the latter being connected to the spur shaft 111 in a manner presently to be explained. The pocket 120 has an abrupt face for making said connection effective; and also an inclined face or wall to force the ball down into the pocket 118, so that the pinion may revolve idly during the forward stroke of the general operator. Said clutch hub 119, it will be observed, is formed upon a bevel gear 121, Fig. 31, which is connected by an idle pinion 122 to another bevel pinion 123, which is loosely mounted on the end of the shaft 111. A collar 124 is fixed on said shaft to confine said pinion 123. Said shaft 111 may be made to rotate in either one direction or the other, according to whether addition or subtraction is being performed, by means of a double clutch member, having one part 125 to engage an internal clutch member 126 provided in the pinion 121, and another part 127 to engage an internal clutch member 128 provided in the pinion 123. This double clutch member is shiftable by the handle 95 73 and rock-shaft 74; the latter having shifter-arms 128^a to engage a peripheral groove 128^b in the clutch member, Fig. 6. Said arms may have pins 128^c to project into the groove, Fig. 31. When the double clutch is in the Fig. 31 position, addition is performed; since the clutch section 126 drives the double member 125 in a direction to carry the spurs to the right or clockwise at Fig. 22, (said double clutch member being connected by a spline 129 to said shaft 111, and the pinion 123 revolving idly). When, however, the double clutch member is shifted out of mesh with clutch section 126 and into mesh with clutch section 128, power is transmitted from pinion 121 through pinions 122 and 123 to the clutch 128, which revolves the double clutch 125, 127 in the opposite direction or counter-clockwise, together with the shaft 111 and the spurs thereon. This brings into play a set of spurs 130, which are effective to turn the pinions 106, 107 and 109 in clockwise direction, that is, in a direction opposite to that in which they turn at the adding operation.

It will be understood that in performing subtraction the computation wheels, including those marked 30, are revolved by the racks 41 to the left at Fig. 22, and that the starting tooth 87, in passing up from the dotted line to the full line position, revolves the pinion 106, and hence the pinions 107 and 109, in clockwise direction, bringing one tooth of pinion 107 into position to be en-

gaged by the spurs 130 during the ensuing rotation of the spur shaft 111. By this means, the pinion 109 is caused to move the gear 110 of next higher denomination or 5 order to the extent of one step, together with its associated dial wheel 30. This movement of gear 110 and dial wheel 30 is counter-clockwise, or in a direction opposite to the adding movements; and hence a lower 10 number appears at the sight-opening 131, Fig. 44; or in other words, 1 is subtracted from the wheel of higher denomination. The movement of pinions 106, 107, 109 is of the same extent whether forward or back- 15 ward, and the same is true of all the computing wheels including the wheels 30.

The movement of shaft 111 is an entire revolution; and it will be understood that when any spur 108, 130 engages and rotates its associated pinion 107, it always leaves said pinion in the position indicated at Fig. 22, with one of its three gaps or blank spaces opposite the spurs, so that the shaft 111 may complete its revolution with- 20 out engagement of said pinion 107 by the opposite spur (130 or 108, as the case may be). In other words, only one of the spurs 108, 130 in each pair can be made to operate a pinion 107 during a single revolution of 25 the shaft 111. Each pair of spurs 108, 130, may be formed of a single piece of sheet metal, Figs. 11 to 20; and the last spur of the series, Fig. 21, may be common to both sets, and is designated as 132. The spurs 30 are placed spirally along the shaft 111, Fig. 4, so that they may act one after another upon the carry-over trains 107, etc. One spiral extends along the shaft 111 in the opposite direction from the other, so that 35 in every case the carry-over train of lowest order may be operated first; then the train of next higher order, and so on.

The three pinions 106, 107, 109, in each tens-carrying train, are like those in the 40 other tens-carrying trains. At Fig. 7 is shown the train that is started by any one of three teeth 87 on the farthings wheel; said train moving to the Fig. 8 position and performing addition; the ensuing movement 45 of the spur 108 bringing it into mesh with the pinion 107, and turning the latter in the manner already explained. This operation occurs three times in each revolution of the farthings wheel 89, in each instance 50 1 being carried over directly to the pence wheel 88. The blind or concealed computing wheel or dummy 104 (Fig. 27) has ten starting teeth 87. It will be understood that any movement that is given thereto will 55 start the carry-over train seen at Fig. 27, to carry 1 onto the pence wheel 88.

Since the driving pinion 133 on the farthings wheel has twelve teeth, and moves one twelfth of a revolution to bring a suc- 60 ceeding digit to the sight opening 131, Fig. 55

44, it will be seen that a complete revolution of said wheel, which may be effected by the four full strokes of the rack 105, will carry twelve farthings or three pence over to the pence wheel 88. At Figs. 3, 4, 4^a and 45, 70 it will be seen that the pinion 107, of the farthings carry-over train, is fixed on a hub 133^a, to the other end of which is fixed a three tooth pinion 133^b which directly engages the gear 110 which is fixed to the 75 pence dial wheel 88, so that carrying-over from the farthings wheel to the pence wheel occurs independently of the dummy wheel 104. The latter is also connected to the same pence gear 110 by a separate tens-carrying 80 train consisting of pinions 106 and 109, which are mounted loosely on the hub 133^a between farthings wheel 107 and pinion 133^b. The pence gear 110 is made of double thickness to accommodate the two pinions 85 109 and 133^b, by either of which it may be operated independently of the other, both pinions 109 and 133^b standing for this purpose out of mesh with gear 110 until rotated by the spurs 108 or 130. At Fig. 45, 90 the gear 110 is just about to be advanced by pinion 133^b; the movement of the latter by the starting tooth on the farthings dial-wheel having been completed. The normal position of pinion 133^b is the same as shown 95 dotted at 109, Fig. 45. The hub 133^a is elongated to reach from the farthings wheel to the pence wheels.

The pence dial wheel 88 has a pinion 97^a corresponding to pinion 133; and both of 100 these pinions are of larger diameter than the pinions 29, in the proportion of twelve to ten, so that the angular movement of the pence and farthings wheels are correspondingly diminished in proportion to the 105 travel of their driving racks. The adding and subtracting racks are spaced a little farther apart to allow for the increased diameter, and properly located with respect to the bar 48, so as to mesh at the same 110 instant as the racks for the ten step dial wheels.

It will be understood that if the machine is set for subtraction, the starting teeth 87 turn the carrying trains in clockwise direction, and the movements of said trains in the same direction are completed by the upper spurs 130; the shaft 111 being, of course, rotated reversely, so that the next higher 115 computation wheel in each instance is rotated reversely to the extent of one point, thus borrowing "1" therefrom, or causing it to show the next lower number at the sight opening 131, Fig. 44.

It will be understood that the ten-step 120 auxiliary or dummy wheel 104 is like all the dial wheels in this respect, that it may be rotated clockwise for addition, or counter-clockwise for subtraction, and that its ten starting teeth 87 will (at each step of said 125

wheel) have the same effect, in either case, as that already referred to in respect to the dial wheels; the lower or upper spur 108 or 130 at Fig. 27 being effective accordingly, 5 so that a penny is either carried over to or borrowed from the pence wheel 88.

It will be seen at Fig. 4, that the pinions 106 and 109, belonging to the pence train, are connected by a long hub 135, to enable 10 the pinion 109 to engage the gear 110, which is fixed to the dial wheel 30 for units of shillings; and the carry-over train between the tens of shillings and pounds has also a long hub 136, to connect the corresponding 15 pinions across the gap 85.

The operation of the tens-carrying train between the units of shillings and tens of shillings wheels 30 and 84, has already been explained in connection with Fig. 22. The 20 tens of shillings dial wheel is seen at Fig. 9, having five starting teeth 87, so that a complete revolution thereof will carry five times to the units of pounds dial wheel. On the tens of shillings rack bar 90, Fig. 26^a, is 25 provided a locking rib or elevation 137 beneath all of the pin-setting linkages 18, except the "1" linkage. Normally the locking rib 137 is ineffective; but when the rear end of the bar 90 is lifted by its linkage 27, said 30 locking rib or elevation becomes effective to lock against movement the linkages 18 from "2" to "9", so that the types associated with said linkages cannot print on the work sheet; thus avoiding liability of error or 35 confusion. The ten pence bar 91, Fig. 26, has a similar locking rib 138 beneath the linkages 18 from "2" to "9", to avoid printing a numeral higher than "1" in the ten-pence column on the work sheet.

40 The farthings rack bar 105 (Fig. 27^a) has a locking rib 139 beneath the linkages 18 extending from "4" to "9", so that nothing greater than three farthings can be written on the work sheet. There is also provided 45 means for preventing a greater number than eleven being either written or computed in the pence columns. The ten-pence pin-carrying bar 91 extends beneath an arm 140, which extends from a rock shaft 141; the 50 latter extending rearwardly beneath the linkages 18, Figs. 30^a, 32, 33, 35 and 36. At each elevation of said bar 91 which is effected by the carriage dog 22, said rock shaft 141 is rocked idly from Fig. 32 position 55 to Fig. 33 position. Upon the lowering of said bar 91 (if no numeral type key has been depressed) the rock shaft 141 is returned to normal position by means of a spring 142, Fig. 32. Of course the keys "2" 60 to "9" are not depressible while the bar 91 is up, as already explained; but if during such elevation of bar 91 the numeral key for "1" is depressed, the special linkage 93 is also depressed, and a toe 143 thereon engages an 65 arm 144 on the opposite side of said rock

shaft 141 from arm 140; and during the further depression of said linkage 93 from the Fig. 33 position to the Fig. 35 position, said rock shaft 141 is forced to rotate farther in the same direction, or toward the 70 left, until a set of stops 145 on said rock shaft is thrown beneath a set of stop ears 146, Fig. 30^a, on bars 19 of the linkages 18 from "2" to "9" inclusive; and the double acting spring 142 holds the rock shaft in the 75 effective Fig. 35 position; so that when the paper carriage 7 moves to position for writing and computing in the units of pence column, no type can be printed, nor can any computing pin 20 be depressed, except the 80 "1" type and the "1" pin. It will be understood, however, that the zero type is not prevented from printing in this column.

The spring 142 is attached at one end to a pin 147 in a fixture, and at the other end to a pin on the end of an arm 148, which is fixed to one end of the rock shaft 141, Fig. 30^a. On the other end of said rock shaft is an arm 149, which vibrates between two stops 150, Figs. 4 and 30^a, to limit the stroke 90 of the rock shaft. A releasing bar 151 is pivoted at 152 upon a fixture, and is releasable by the farthings rack 105, as the latter rises under the influence of the carriage dog 22; so that the type keys 2 and 3 95 may be operated in the farthings column. Said bar 151 has a finger 153 to engage the arm 140 on said rock shaft to move it from the Fig. 35 position toward the Fig. 36 normal position; such movement of the rock-shaft being completed by the spring 142, whereby the linkages are released from the 100 control of the stop arms 145. There is also provided upon the pin-operating bar 36 of the general operator a cam 155, Fig. 30^a, 105 which during the movement of the general operator may engage a finger 156 upon the releaser 151, and cause the same to release the locks 145, as will be understood by inspection of Fig. 36. A spring 156^a returns 110 arm 153 to normal position against stop 156^b.

For setting the dial wheels to zero, there is provided through an arbor 157, Figs. 4, 5, 37, and 43, which extends through the 115 hubs of the dial wheels, and is operated by a pinion 158, provided upon the arbor or shaft and constantly engaging a rack 159 upon a bar 160, which corresponds to the rack bars 21, and has at its rear end a single 120 pin 161, engageable by the pin-driving bar 36, so that the general operator may be used for turning the wheels to zero. On the forward stroke of the general operator, the pinion 158 and its arbor are turned in one 125 direction; and upon the return stroke of the general operator, the pinion and arbor are returned to normal positions; said bar 160 having a shoulder 162, which is engaged by the rack-returning bar 37 upon the return 130

stroke of the general operator. A spring detent 163 engages a depression 164 on a wheel 165, which is fixed on the arbor, to hold the same in normal position.

- 5 Each of the dial wheels, Fig. 22, has a recess 166 to receive a ball 167; the ball being pressed into the recess by a spring 168, so that the arbor may carry the wheel toward zero position; the ball forming a
- 10 clutch between the arbor and the wheel, corresponding to that seen in Fig. 34. These balls and springs are seated in pockets 169; said pockets being formed in collars which are mounted on or carried by said arbor 157.
- 15 The ball-carrying collar for the pounds wheel is indicated as 170, and may be secured to the arbor by a set screw 171, Fig. 43, or it may be formed directly upon the arbor. A short collar 172 is provided with
- 20 one pocket 169 for the tens of shillings computing wheel. This collar 172 is loose on the arbor, to permit rotation of the arbor to a certain extent while the tens of shillings wheel is stationary. Another collar
- 25 173 is provided with two pockets 169, for the units of shillings wheel and the double pence-wheel, respectively; said collar 173 being secured to the arbor 157 by a set screw 174. Still another collar 175 is pro-
- 30 vided with a pocket 169 for the farthings wheel; this collar being also loose on the arbor 157, and confined by a fast collar 175a. The reason for making the collars 172 and 175 loose, is that it is not desired
- 35 to turn the tens of shillings wheel more than one-tenth of a revolution, or the farthings wheel more than one-third of a revolution, during an entire revolution of the arbor 157; and so it is arranged that these wheels
- 40 shall not be picked up until the latter part of the initial revolution of said shaft 157.

At the end of the collar 173 is fixed a pin 176, Figs. 37-40, 43 which normally occupies the position at Fig. 37. The arbor 157 makes two-thirds of a revolution idly, so far as the farthings wheel is concerned, and then the pin 176 engages a lug 177 on collar 175, as at Fig. 38, and during the final portion of the revolution of said arbor 157, said

- 50 pin turns the collar to the Fig. 40 position, together with the farthings wheel 89; thus giving the latter one-third of a revolution, or less, according to the original position of the wheel 89; but in any event the tooth
- 55 87 on said wheel starts the associated carry-over train 106, in the manner hereinbefore explained.

It will be seen that the farthings wheel 89 has three of the recesses or notches 166, located at intervals at 120 degrees, so that it is insured that the loose or short-stroke collar 175 will always turn the farthings wheel 89, regardless of the original position of the latter, as there are three points in the revo-

lution of 89 at which it can be picked up by 65 the clutching ball 167. It will be understood that during the return stroke of the general operator 32, it is intended that all of the carry-over trains shall operate; the effect of the rotation of the zeroizing arbor 70 157 being to set all the remaining computation wheels each within one point of its zero position, and to start the lowest carry-over train, which has its pinion started by the farthings wheel, the starting of this train 75 causing the next higher wheel to turn to zero, and simultaneously to start its own carry-over train, thus causing the next higher wheel to turn to zero and start its carry-over train, and so on, so that all of 80 the wheels are brought one after another to zero during the return stroke of the general operator. It will be understood that the auxiliary wheel 104 has no clutch connection with the zeroizing arbor 157. It will 85 be understood that the recess 166 in the pence wheel is so placed that the zeroizing arbor 157 moves said wheel to such a point that "11" appears at the sight opening. The loose collar 172 for tens of shillings is operated by a pin 178, similar to pin 176, and has a lug 179 corresponding to lug 177, but shorter, as there is more lost motion on the arbor 157 relative to the loose collar 172, since said collar is not turned more than 90 one-tenth of a revolution by the pin 178. Said tens of shillings wheel 84 has five of the ball recesses 166, at equal intervals, Fig. 9; and if said wheel 84 shows "0" or a blank through the sight opening the zeroizing arbor or shaft 157 will rotate the wheel 84 one point, bringing "1" to the sight opening, and during the subsequent movement of the general operator 32, said wheel 84 will be advanced another point, bringing 100 "0" to the sight opening, and starting the carry-over train. If, however, said wheel 84 shows "1" at the operation of the zero shaft 157, the shaft will not move the wheel.

From the foregoing it will be understood 110 that at the first stroke of the shaft 157, all the wheels, from the pence wheel up, are advanced each to a position which is one point short of the zero position; while the farthings wheel is advanced fully to the zero position, to start its carry-over train; and that during the return stroke of the general operator all the carry-over trains (except that belonging to the dummy wheel) are brought 115 into use, and hence all of the dial wheels 120 are brought to zero. During said return stroke of the general operator, the rack bar 160 returns, being carried back by means of the cross bar 37 engaging lug 162 on said rack bar, and the zeroizing pinion 158 is 125 also returned, and hence the arbor 157 is rotated back to its initial position. During this reverse movement the pins 176 and 178

rotate idly for most of the distance and during the final portion of the movement, said pins engage the lugs 177 and 179 and return the loose collars 175 and 172 idly to 5 their normal positions, which are diagrammatically indicated at Fig. 43, the parts being shown slightly separated along the arbor, for convenience of illustration.

When subtraction is being effected, the 10 ball clutches just referred to between the zeroizing arbor or shaft 157 and the dial wheels, are silenced, so as to permit the dial wheels to rotate reversely, for subtraction. This effect is produced by shifting arbor 157 15 endwise. For this purpose the arbor is provided in its end with a groove 180, Figs. 6 and 43, which is engaged by pins 181 on arms 83 fixed to said rock shaft 74, so that when it is rocked to set the machine to subtraction, the zeroizing arbor 157 is shifted, 20 and the clutching balls aforesaid are silenced. For this purpose the shaft 157 is shifted to the right at Fig. 5, together with all collars thereon, and the balls 167 are carried 25 into engagement with conelike depressions or cups 183 in the adjacent hubs of the dial wheels of their associated wheels; the walls of these cups being inclined, so that the balls are forced thereby to sink into the 30 collars 170, 172, 173, 175, as indicated in dotted lines at Fig. 5, so that the clutches are silenced. The zeroizing pinion 158 is fixed to the detent wheel 165 and these two 35 wheels have a key 184, Fig. 4, to slide in a keyway 185 in the collar 170, which is fixed on arbor 157, thus permitting the arbor to shift endwise for subtraction while the 40 said pinion and detent wheel remain stationary. The rack-shifting bar 48 does not 45 control the zeroizing rack 160, but the latter has a guide 187, Figs. 4 and 30.

The zero-setting key is numbered 188, Fig. 25, and has a stem 189, to depress an arm 190 on a rock shaft 191, which extends 45 across the machine, and also has an arm 192 provided with a wrist 193, which lifts said zero-setting bar 160, causing the pin 161 thereon to encounter a fixed obstruction 194, whereby the pin 161 is arrested, and 50 hence is displaced relatively to the bar 160, as the latter continues to ascend. The zero key 188 is then released, and the bar 160 dropped, and the general operating handle 31 is operated to turn the wheels to zero, 55 as aforesaid. Upon said shaft 191 is an arm 195, which by means of a link 197 operates an arm 196 upon the subtraction-shifting shaft 74, so that the latter is automatically shifted to original position, and hence all 60 the clutches between the zeroizing shaft 157 and the dial wheels are rendered effective for the zeroizing operation. The usual plate 198 is operated to restore the computation pins to normal positions on the rack bars,

at the completion of the return stroke of 65 the general operator, in the usual manner. Arm 195 is loose upon shaft 191, but is operated by a pin 191^a (Fig. 6) fixed in the shaft and playing in a slot 191^b in the hub of the arm. The slot permits the lever 73 70 to operate without effecting the shaft 191, when necessary. Link 93 is bent at 199 to clear pin or stop 194.

Variations may be resorted to within the 75 scope of the invention, and portions of the improvements may be used without others.

Having thus described my invention, I claim:

1. The combination with computing 80 wheels having pinions, of shiftable means individual to said pinions for turning the same forwardly or backwardly, key-controlled means for determining the extent of rotation of said pinions, a general operator arranged to directly and positively drive 85 all of said shiftable means, and shifting means dependent upon the movement of said general operator for determining the direction of rotation of the pinions at the operation of said general operator by shifting 90 said shiftable means selectively in one of two directions.

2. The combination with computing 95 wheels having pinions, of addition and subtraction racks for each pinion, said racks normally out of mesh, a general operator arranged to directly and positively drive all 100 of said racks, and means rendered effective by said general operator at the beginning of its movement for moving one or the other set of racks into engagement with the pinions.

3. The combination with computing 105 wheels having pinions, of addition and subtraction racks for each pinion, said racks normally out of mesh, a general operator arranged to directly and positively drive all 110 of said racks, means rendered effective by said general operator at the beginning of its movement for moving one or the other set of racks into engagement with the pinions, and adjustable means to determine which set of racks shall be engaged with the pinions.

4. The combination with computing 115 wheels having pinions, of a double rack for each pinion, a bar connected to all the racks to shift them into and out of mesh with the pinions, a general operator arranged to directly and positively drive all of the racks, and adjustable means to enable said general operator to control said bar.

5. The combination with computing 125 wheels having pinions, of a double rack for each pinion, a bar connected to all the racks to shift them into and out of mesh with the pinions, a general operator arranged to directly and positively drive all of the racks,

adjustable means to enable said general operator to control said bar, said racks having longitudinal slots engaged by said bar, and swinging arms carrying said bar, said adjustable means including cam mechanism to swing said arms.

6. The combination with computing wheels having pinions, of a double rack for each pinion, said racks normally disengaged from the pinions, a bar connected to all the racks to shift them into mesh with the pinions, a general operator arranged to directly and positively drive all of said racks, a device to drive said general operator, means connected to said driving device for shifting said racks into mesh with the pinions in advance of the movement of said general operator, and adjustable means to determine which racks shall be shifted into engagement with the pinions.

7. The combination of a set of computing wheels, shiftable means individual to said computing wheels for rotating the same, said rotating means normally disconnected from the computing wheels, a general operator arranged to directly and positively drive all of said wheel-rotating means, a driver for said general operator, means connected to said driver to shift said wheel-rotating means to effective position in advance of the movement of the general operator, and adjustable means for determining whether the computing wheels shall be turned forwardly or backwardly.

8. The combination of a set of computing wheels, shiftable means individual to said computing wheels for rotating the same, said rotating means normally disconnected from the computing wheels, a general operator arranged to directly and positively drive all of said wheel-rotating means, a driver for said general operator, means connected to said driver to shift said wheel-rotating means to effective position in advance of the movement of the general operator, adjustable means for determining whether the computing wheels shall be turned forwardly or backwardly, said driver including a drive shaft or axle having a lost-motion connection to said general operator, and a cam mechanism connected to said drive shaft or axle to control the shifting of the wheel-rotating means into engagement with the wheels.

9. The combination of a set of computing wheels, shiftable means for rotating the computing wheels, said rotating means normally disconnected from the computing wheels, a general operator connected to said wheel-rotating means, a driver for said general operator including a hollow shaft provided with gears and also including racks entrained with said gears, a sleeve upon said hollow shaft, said sleeve controlled by said shaft, and a cam device upon said sleeve to

shift said wheel-rotating means, and a drive-shaft within said hollow shaft and loosely connected thereto, and also connected to said sleeve to start the same in advance of said hollow shaft.

10. The combination of a set of computing wheels, shiftable means for rotating the computing wheels, said rotating means normally disconnected from the computing wheels, a general operator connected to said wheel-rotating means, a driver for said general operator including a hollow shaft provided with gears and also including racks entrained with said gears, a sleeve upon said hollow shaft, said sleeve controlled by said shaft, a cam device upon said sleeve to shift said wheel-rotating means, a drive-shaft within said hollow shaft and loosely connected thereto, and also connected to said sleeve to start the same in advance of said hollow shaft, and means for adjusting said cam device for either addition or subtraction.

11. The combination of a set of computing wheels, shiftable means for rotating the computing wheels, said rotating means normally disconnected from the computing wheels, a general operator connected to said wheel-rotating means, a driver for said general operator including a hollow shaft provided with gears and also including racks entrained with said gears, a sleeve upon said hollow shaft, said sleeve controlled by said axle, a cam device upon said sleeve, an arm having a part to engage said cam device, said arm forming part of said shiftable means for rotating the computing wheels, a drive shaft within said hollow shaft and loosely connected thereto and also connected to said sleeve to start the same in advance of said hollow shaft; said cam device constructed to release said arm during the rotation of the shafts, and a spring to return the arm to normal position when released by said cam.

12. The combination of a set of computing wheels, shiftable means for rotating the computing wheels, said rotating means normally disconnected from the computing wheels, a general operator connected to said wheel-rotating means, said general operator including both a hollow shaft provided with gears and racks entrained with said gears, a sleeve upon said hollow shaft, said sleeve controlled by said axle, a cam device upon said sleeve, an arm having a part to engage said cam device, said cam device forming part of said shiftable means for rotating the computing wheels, a drive shaft within said hollow shaft and loosely connected thereto and also connected to said sleeve to start the same in advance of said hollow shaft; said cam device constructed to release said arm during the rotation of the shafts, and a spring to return the arm to normal position.

when released by said cam, said cam mounted to yield and pass said arm on the return stroke of said shafts.

13. The combination of a set of computing wheels, shiftable rotating devices normally disconnected from the computing wheels, a general operator connected with said rotating means, a drive shaft loosely connected to said general operator whereby 10 said drive shaft may start in advance of said general operator, a sleeve surrounding said drive shaft and connected thereto to rotate therewith, a cam on said sleeve, an arm operated by said cam and forming part 15 of said means for shifting said wheel-rotating devices, said cam constructed to release the arm during the rotation of the drive-shaft, and a spring to return the arm to normal position when released; one of said cam 20 and arm elements being mounted to yield to permit the cam to pass the arm on the return stroke of the driver.

14. The combination with computing wheels having pinions, of a rack for driving each pinion, said racks normally disengaged from the pinions, a bar connected to all the racks to shift them into mesh with the pinions, an arm connected to said bar to operate the same, a reciprocating general operator, a driver for said general operator including a hollow shaft and also including a drive shaft within said hollow shaft and having a lost-motion connection thereto, a sleeve upon said hollow shaft, said sleeve 35 connected to said drive-shaft, a cam upon said sleeve to operate said rack-controlling arm, said cam constructed to release said arm, one of said cam and arm elements being mounted to yield to enable one to pass 40 the other during the return stroke of the general operator, and means for returning said arm to normal position.

15. The combination with computing wheels having pinions, of addition and subtraction racks or drivers for each pinion, said racks normally disengaged from the pinions, a bar connected to all the racks to shift either set thereof into mesh with the pinions, arms connected to said bar and effective 45 in alternation to operate the same, a reciprocating general operator, a driver for said general operator including a hollow shaft, a drive shaft within said hollow shaft and having a lost-motion connection thereto, a sleeve upon said hollow shaft, said sleeve 50 connected to said drive shaft, addition and subtraction cams upon said sleeve to operate said rack-controlling arm, said cams constructed to release said arms, and being 55 mounted to yield to enable the arms to pass them during the return stroke of the general operator; a spring device for returning said arms to normal position, and means for rendering either cam effective and silencing 60 the other.

16. The combination of a set of computing wheels, devices shiftable for rotating the computing wheels in either forward or backward direction; said rotating devices normally disconnected from the computing 70 wheels, a reciprocating general operator connected with said rotating devices, a drive shaft loosely connected to said general operator, whereby said drive shaft may start in advance of said general operator, a sleeve 75 surrounding said drive shaft and connected thereto to rotate therewith, addition and subtraction cams on said sleeve, means for shifting said wheel rotating devices, said shifting means including arms operable by 80 said cams in alternation, and each cam constructed to release its arm during the advance rotation of the drive shaft, and a spring to return the arms to normal positions when released; said cams mounted to 85 yield to permit the arms to pass on the return stroke of the driver, and means for rendering either cam effective and silencing the other.

17. The combination of a set of computing 90 wheels, devices shiftable for rotating the computing wheels in either forward or backward direction, said rotating devices normally disconnected from the computing wheels, a reciprocating general operator 95 connected with said rotating means, a drive shaft loosely connected to said general operator, whereby said drive shaft may start in advance of said general operator, a sleeve surrounding said drive shaft and connected 100 thereto to rotate therewith, addition and subtraction cams on said sleeve, arms forming part of means for shifting said wheel rotating devices, said arms operable by said cams in alternation, and each cam constructed 105 to release its arm during the advance rotation of the drive shaft, and a spring to return the arms to normal positions when released, said cams mounted to yield, to permit the arms to pass on the return stroke of 110 the driver, and means for shifting said sleeve endwise upon said shaft, to silence either cam and render the other effective.

18. The combination of a set of computing wheels having pinions, a set of rack bars, 115 each bar having two racks for rotating its associated pinion either forwardly or backwardly, said rack bars normally disengaged from the pinions and having longitudinal slots, a rocking frame comprising a bar 120 passing through said slots to shift the racks into and out of engagement with the pinions, means including a reciprocating general operator for driving said rack bars, a drive shaft loosely connected to said general operator to start in advance thereof, arms upon 125 said rocking frame, a sleeve surrounding said drive shaft and connected thereto to rotate therewith and extending between said arms, and addition and subtraction cams ad- 130

ja⁷⁰cent to said arms and mounted on said sleeve, said sleeve shiftable along the shaft to engage either cam with its arm and disengage the other cam from its arm.

5 19. The combination of a set of computing wheels having pinions, a set of rack bars, each bar having two racks for rotating its associated pinion either forwardly or backwardly, said rack bars normally disengaged 10 from the pinions and having longitudinal slots, a rocking frame comprising a bar passing through said slots to shift the racks into and out of engagement with the pinions, means including a reciprocating general operator for driving said rack bars, a drive shaft loosely connected to said general operator to start in advance thereof, arms upon said rocking frame, a sleeve surrounding said drive shaft and connected thereto to 20 rotate therewith and extending between said arms, addition and subtraction cams adjacent to said arms and mounted on said sleeve, said sleeve shiftable along the shaft to engage either cam with its arm and disengage the other cam from its arm; each cam having a curved dwell or dead portion to hold the racks in mesh with the pinions during the 25 advance of the general operator, and constructed to release its arm during the advance rotation of the drive shaft, and a spring device to return the frame to midway normal position when released.

20. The combination of a set of computing wheels having pinions, a set of rack bars, 35 each bar having two racks for rotating its associated pinion either forwardly or backwardly, said rack bars normally disengaged from the pinions and having longitudinal slots, a rocking frame comprising a bar 40 passing through said slots to shift the racks into and out of engagement with the pinions, means including a reciprocating general operator for driving said rack bars, a drive shaft loosely connected to said general operator to start in advance thereof, arms upon said rocking frame, a sleeve surrounding said drive shaft and connected thereto to rotate therewith and extending between said arms, addition and subtraction 45 cams adjacent to said arms and mounted on said sleeve, said sleeve shiftable along the shaft to engage either cam with its arm and disengage the other cam from its arm; each cam having a curved dwell or dead 50 portion to hold the racks in mesh with the pinions during the advance of the general operator, and constructed to release its arm during the advance rotation of the drive shaft, and a spring device to return the frame to midway 55 normal position when released; said cams mounted to yield to permit the arms to pass on the return stroke of the general operator.

21. The combination with numeral keys, 65 linkages operable thereby, a nest of pins

settable by said linkages and bars bearing said pins, of means for displacing the pin-carrying bars *seriatim*, a carriage connected to said displacing means, computation wheels operable by said bars, a general operator for operating the bars and wheels; one of said bars having a single "10" pin ex- 70 jacent from the remaining pins, said linkages including a linkage for setting said "10" pin, and said "10" linkage connected with the linkage which sets the "1" pin; each of said linkages comprising a pair of cranks and two links connecting said cranks, and a key-operated rock-shaft for driving each linkage, the "1" linkage and said "10" 75 linkage having a common rock shaft; and said computation wheels including a special wheel operable by said "10" bar and constructed to move more than ten and less than twenty steps in one revolution.

22. The combination with number wheels, bars to operate them, and a general operator for operating the bars and wheels, of numeral keys, linkages operable thereby, pins from "1" to "9" on said bars settable 90 by said linkages; one of said bars having means for turning one of said wheels ten steps; said ten-step bar having a single pin extraneous or exjacent from said "9" pins; said linkages including a linkage for setting said single pin, said single-pin-linkage connected to the linkage which sets the "1" pins, and a carriage having means for displacing the pin-carrying bars.

23. The combination with an irregular 100 computing wheel constructed to advance more than ten and less than twenty steps in each cycle of its movements, of a rack entrained with said wheel, key-set pins on said rack, means to advance said rack and wheel 105 to variable extents determined by the setting of said pins, and a driving bar having a key-set pin extraneous to said pins, and having means to engage and move said rack to rotate said wheel ten steps.

24. The combination with a pence wheel, 110 means including key-set devices for rotating said wheel any number of steps from two to eleven inclusive, a supernumerary or dummy wheel, key-set means for advancing said dummy wheel only a single step, and a carry-over train operated between said dummy wheel and said pence wheel at every movement of the dummy wheel.

25. The combination with a pence wheel 115 having a pinion, of a bar having a key-set 10 pin, a second bar having key-set pins from "2" to "9" inclusive, and also having a rack to mesh with said pinion, a third bar having only one pin, and also having a rack, a dummy wheel having a pinion operable by the last-mentioned rack, a carry-over train between said dummy wheel and said pence wheel and operable at every movement of the dummy wheel, a connection be- 120 125

5 tween said first and second bars to enable the former to drive the latter, a carriage having means to displace said first two bars, to permit the pins to be set thereon, and a connection between said second and third bars to enable the second bar to cause the third bar to be displaced for the pin-setting operation.

26. The combination with a pence wheel 10 having a pinion, of a bar having a key-set 15 pin, a second bar having key-set pins from "2" to "9" inclusive, and also having a rack to mesh with said pinion, a third bar having only one pin, and also having a rack, 20 a dummy wheel having a pinion operable by the last-mentioned rack, a carry-over train between said dummy wheel and said pence wheel and operable at every movement of the dummy wheel, a connection between 25 said first and second bars to enable the former to drive the latter, a carriage having means to displace said first two bars, to permit the pins to be set thereon, a connection 30 between said section and third bars to enable the second bar to cause the third bar to be displaced for the pin-setting operation, a farthings wheel, and a carrying-over train from said farthings wheel to said dummy wheel.

30 27. A computing mechanism comprising a series of computing wheels, keys to determine the extent of rotation thereof, carry-over mechanism for said wheels, all of said wheels provided with dials, a wheel 35 unprovided with a dial and controlled only by one of said keys and movable only one step at each operation, and a carry-over device effective at each movement of the last-mentioned wheel to carry over to the next higher 40 wheel of said series.

28. The combination with numeral type keys, a set of computation pins settable thereby, dial wheels including a wheel for computing tens of shillings, and bars carrying said pins and connected to said wheels, 45 of a carriage, means connected to the carriage for lifting or displacing the bars successively to enable the pins thereon to be set by the keys, and a rib or elevation on the 50 tens of shillings bar, to lock all of the keys from "2" to "9" inclusive, to prevent their types from printing.

29. The combination with numeral type keys, a set of computation pins settable 55 thereby, dial wheels including a ten-pence wheel and bars carrying said pins and connected to said wheels, of a carriage, means connected to the carriage for lifting or displacing the bars successively to enable the 60 pins thereon to be set by the keys, and a rib or elevation on the ten-pence bar to lock all of the keys from "2" to "9" inclusive to prevent their types from printing.

30. The combination with numeral type 65 keys, a set of computation pins settable

thereby, dial wheels and bars carrying said pins and connected to said wheels, one of said bars being connected to a farthings wheel, of a carriage, means connected to the carriage for lifting or displacing the bars 70 successively to enable the pins thereon to be set by the keys, and a rib or elevation on said farthings bar to lock all of the keys from "4" to "9" inclusive, to prevent their types from printing.

75 31. The combination with dial wheels, including wheels for computing pence, of keys for controlling the extent of rotation of said wheels, types operated by said keys, and means for preventing printing of more than 80 11 in the pence column on the work sheet.

32. The combination with dial wheels, including wheels for computing pence, of keys, types operated by said keys, computation pins set by said keys, wheel-controlling bars 85 upon which said computation pins are mounted, a general operator for said bars, a carriage, means connected to said carriage for elevating or displacing said bars in succession to enable the keys to set the pins 90 thereon, said bars including a ten-pence bar and a pence-bar, said ten-pence bar having one pin thereon, a rock shaft having an arm rocked idly by said ten-pence bar when the latter is displaced by said carriage, means 95 dependent upon the setting of the ten-pence pin for rocking said shaft farther to its effective position, and means upon said shaft for locking type keys from "2" to "9" against printing or computing when the 100 carriage is in position for printing in the pence column.

33. The combination with dial wheels, including wheels for computing pence, of keys, types operated by said keys, computation pins set by said keys, wheel-controlling bars upon which said computation pins are mounted, a general operator for said bars, a carriage, means connected to said carriage

105 for elevating or displacing said bars in succession to enable the keys to set the pins thereon, said bars including a ten-pence bar and a pence bar, said ten-pence bar having one pin thereon, a rock shaft having an arm rocked idly by said ten-pence bar when the latter is displaced by said carriage, means 110 dependent upon the setting of the ten-pence pin for rocking said shaft farther to its effective position, means upon said shaft for locking type keys from "2" to "9" against 115 printing or computing when the carriage is in position for printing in the pence column, and means for releasing said locking means.

34. The combination with dial wheels, including wheels for computing pence and farthings, of keys, types operated by said keys, computation pins set by said keys, wheel-controlling bars upon which said computation pins are mounted, a general operator for said bars, a carriage, means connect- 125 130

ed to said carriage for elevating or displacing said bars in succession to enable the keys to set the pins thereon, said bars including a ten-pence bar, a pence bar and a farthing bar, said ten-pence bar having one pin thereon, a rock shaft having an arm rocked idly by said ten-pence bar when the latter is displaced by said carriage, means dependent upon the setting of the ten-pence pin for 10 rocking said shaft farther to its effective position, means upon said shaft for locking type keys from "2" to "9" against printing or computing when the carriage is in position for printing in the pence column, and 15 means connected to the farthings bar for releasing said locking means.

35. The combination with dial wheels, including wheels for computing pence, of keys, types operated by said keys, computation 20 pins set by said keys, wheel-controlling bars upon which said computation pins are mounted, a general operator for said bars, a carriage, means connected to said carriage for elevating or displacing said bars in succession to enable the keys to set the pins thereon, said bars including a ten-pence bar and a pence bar, said ten-pence bar having one pin thereon, a rock shaft having an arm rocked idly by said ten-pence bar when the latter is displaced by said carriage, means 25 dependent upon the setting of the ten-pence pin for rocking said shaft farther to its effective position, means upon said shaft for locking type keys from "2" to "9" against 30 printing or computing when the carriage is in position for printing in the pence column, and means connected to the general operator for releasing said locking means.

36. The combination with dial wheels, including wheels for computing pence, of keys, types operated by said keys, linkages operated by said keys, computation pins set by said linkages, wheel-controlling bars upon which said computation pins are 40 mounted, a general operator for said bars, a carriage, means connected to said carriage for displacing said bars in succession to enable the keys to set the pins thereon, said bars including a ten-pence bar and a 45 pence bar, said ten-pence bar having one pin thereon, a rock shaft having an arm rocked idly by said ten-pence bar when the latter is displaced by said carriage, means dependent upon the setting of the ten-pence 50 pin by its key for rocking said shaft farther to its effective position, said shaft-rocking means projecting upon the linkages from "2" to "9" inclusive, arms upon said rock shaft to intercept said projections when the 55 rock shaft is in effective position, a double-acting spring for holding said rock shaft in its effective position, and means for automatically restoring said rock shaft to normal position after the opportunity has

passed for computation in the pence 65 column.

37. The combination with dial wheels, including wheels for computing pence, of keys, types operated by said keys, linkages operated by said keys, computation pins set by 70 said linkages, wheel-controlling bars upon which said computation pins are mounted, a general operator for said bars, a carriage, means connected to said carriage for displacing said bars in succession to enable the 75 keys to set the pins thereon, said bars including a ten-pence bar and a pence bar, said ten-pence bar having one pin thereon, a rock shaft having an arm rocked idly by said ten-pence bar when the latter is displaced by 80 said carriage, means depending upon the setting of the ten-pence pin by its key for rocking said shaft farther to its effective position, said shaft-rocking means projecting upon the linkages from "2" to "9" inclusive, 85 arms upon said rock shaft to intercept said projections when the rock-shaft is in effective position, a double-acting spring for holding said rock-shaft in its effective position, and a lever for restoring said rock-shaft to normal position, said lever having an arm engageable by either the pence bar or the general operator, for actuating said lever.

38. In a computing mechanism for an 95 irregular monetary or measuring system, the combination of a set of carry-over trains, a set of computing wheels, a certain one of said wheels having fewer steps than the others in each of its cycles of movements, 100 said certain wheel also having means for starting its carry-over train once in each cycle, an arbor for said wheels, clutches between said arbor and said wheels, said certain wheel having means for becoming 105 clutched to said arbor at a plurality of points in each revolution of the wheel, means for permitting said certain wheel to stand stationary while the arbor is turning part of its revolution, and to be turned by said arbor during the remainder of the revolution thereof, and means to operate said arbor to re-set all of said wheels.

39. In a mechanism for computing according to the British monetary standard, 115 the combination of a set of carry-over trains, a set of computing wheels including a farthings wheel, said farthings wheel constructed to move four steps in each of its cycle of movements, and having means for starting its carry-over train three times in each revolution, an arbor for said wheels, clutches between said arbor and said wheels, said farthings wheel having means for becoming clutched to said arbor at three equidistant points upon the wheel, and a lost-motion connection between said arbor and said farthings wheel, so that the arbor may 120 125

turn other wheels while the farthings wheel is stationary, and may then turn said farthings wheel together with the other wheels.

40. In a mechanism for computing according to the British monetary standard, the combination of a set of carry-over trains, a set of computing wheels including a tens of shillings wheel, said tens of shillings wheel constructed to move two steps in each 10 of its cycle of movements, and having means for starting its carry-over train five times in each revolution, an arbor for said wheels, clutches between said arbor and said wheels, said tens of shillings wheel having means 15 for becoming clutches to said arbor at five equidistant points upon the wheel, and a lost-motion connection between said arbor and said tens of shillings wheel, so that the arbor may turn other wheels while the tens 20 of shillings wheel is stationary, and may then turn said tens of shillings wheel together with the other wheels.

41. In a mechanism for computing according to the British monetary standard, the combination of a set of carry-over trains, a set of computing wheels including a farthings wheel, said farthings wheel constructed to move four steps in each of its cycle of movements and having means for starting 30 its carry-over train three times in each revolution, an arbor for said wheels, clutches between said arbor and said wheels, a loose collar on said arbor for said farthings wheel, the latter having means for becoming 35 clutched to said collar at three equidistant points upon the wheel, and a lost-motion connection between said arbor and said collar, so that the arbor may turn other 40 wheels while the farthings wheel and collar are stationary, and may then turn said farthings wheel and collar, together with the other wheels.

42. In a mechanism for computing according to the British monetary standard, the combination of a set of carry-over trains, a set of computing wheels including a tens of shillings wheel, said tens of shillings wheel constructed to move two steps in each of its cycle of movements and having means 50 for starting its carry-over train five times in each revolution, an arbor for said wheels, clutches between said arbor and said wheels, a loose collar on said arbor for said tens of shillings wheel, the latter having means for becoming 55 clutched to said collar at five equidistant points upon the wheel, and a lost-motion connection between said arbor and said collar, so that the arbor may turn other wheels while the tens of shillings 60 wheel and collar are stationary, and may then turn said tens of shillings wheel and collar together with the other wheels.

43. The combination with a set of computing wheels, of shiftable means for ro-

tating them either forwardly or backwardly, 6, a zero-setting arbor for said wheels, means including clutches between the wheels and the arbor to enable the arbor to set the wheels back concomitantly, and means for moving the arbor endwise, said wheels having 70 hubs provided with coned cups to engage the clutch members and cam them to ineffective positions, to permit the wheels to be rotated backwardly for subtraction.

44. The combination with a set of computing wheels, of shiftable means for rotating them either forwardly or backwardly, 75 a zero-setting arbor for said wheels, means including clutches between the wheels and the arbor to enable the arbor to set the 80 wheels back concomitantly, means for moving the arbor endwise, said wheels having hubs provided with coned cups to engage the clutch members and cam them to ineffective positions, to permit the wheels to be 85 rotated backwardly for subtraction, a zero key for beginning the operation of setting the wheels back to zero, and means connected to said zero key for restoring said arbor endwise to normal position. 90

45. The combination with a set of computing wheels, of shiftable means for rotating them either forwardly or backwardly, 95 a zero-setting arbor for said wheels, means including clutches between the wheels and the arbor to enable the arbor to set the 100 wheels back concomitantly, means for moving the arbor endwise, said wheels having hubs provided with coned cups to engage the clutch members and cam them to ineffective positions, to permit the wheels to be rotated backwardly for subtraction, and a single handle having means for shifting said arbor endwise and setting the machine for subtraction. 105

46. The combination with a pence wheel, means including key-set devices for rotating said wheel any number of steps from two to eleven inclusive, a supernumerary or dummy wheel, key-set means for advancing 110 said dummy wheel only a single step, a carry-over train operated between said dummy wheel and said pence wheel at every movement of the dummy wheel, a farthings wheel, means including key-set devices for 115 rotating said farthings wheel, and a carry-over train extending directly from said farthings wheel to said pence wheel to operate independently of said dummy wheel.

47. The combination with a pence wheel, 120 means including key-set devices for rotating said wheel any number of steps from two to eleven inclusive, a supernumerary or dummy wheel, key-set means for advancing 125 said dummy wheel only a single step, a carry-over train operated between said dummy wheel and said pence wheel at every movement of the dummy wheel, a farthings

wheel, means including key-set devices for rotating said farthings wheel, and a carry-over train extending directly from said farthings wheel to said pence wheel to operate independently of said dummy wheel, said farthings carry-over train including two pinions and a long hub fixedly connecting them, and said dummy carry-over train including two pinions fixed together and loosely mounted on said hub between said farthings pinions.

48. The combination with a pence wheel, means including key-set devices for rotating said wheel any number of steps from two to eleven inclusive, a supernumerary or dummy wheel, key-set means for advancing said dummy wheel only a single step, a carry-over train operated between said dummy wheel and said pence wheel at every movement of the dummy wheel, a farthings wheel, means including key-set devices for rotating said farthings wheel, and a carry-over train extending directly from said farthings wheel to said pence wheel to operate independently of said dummy wheel, said farthings carry-over train including two pinions and a long hub fixedly connecting them, and said dummy carry-over train including two pinions fixed together and loosely mounted on said hub between said farthings pinions, said pence wheel comprising a gear of sufficient thickness to accommodate pinions in both of said carry-over trains, but the last mentioned pinions being normally out of engagement with said pence gear, to permit either of them to rotate said pence gear independently of the other.

49. The combination, with a set of numeral keys, including the usual "1" key; of a series of denominational computing wheels, including an ultra-decimal wheel comprising separate members for computing in the units and tens columns of the denomination to which said ultra-decimal wheel relates; and means for driving said wheels to the extents determined by the keys depressed, said driving means including devices for effecting movement of both members of said ultra-decimal wheel.

50. The combination of three index-pin racks or bars, and a pence wheel with which they are associated, the first of said bars being assigned to compute only ten pence, the second being assigned to compute from two to nine pence, and the third being assigned to compute a single penny.

51. The combination of three index-pin racks or bars, and a pence wheel with which they are associated having a pinion thereon, the first of said bars being assigned to compute only ten pence, the second being assigned to compute from two to nine pence, and the third being assigned to compute a single penny; said first bar having no rack teeth, and said second bar being driven

by the first, the second bar having a rack to mesh with the said pinion on the pence wheel.

52. The combination of three index-pin racks or bars, a pence wheel with which they are associated having a pinion thereon, and a special computation wheel adjacent said pence wheel having a pinion thereon, but having no dial, the first of said bars being assigned to compute only ten pence, the second being assigned to compute from two to nine pence, and the third being assigned to compute a single penny; said first bar having no rack teeth, and said second bar being driven by the first, the second bar having a rack to mesh with the pinion on the pence wheel, and said third bar having a rack in mesh with the pinion on the special computation wheel; said special wheel being provided with a carry-over train which operates every time that the special wheel is operated.

53. The combination of three index-pin racks or bars, keys for setting the index pins, a pence wheel with which said bars are associated having a pinion thereon, and a special computation wheel adjacent said pence wheel having a pinion thereon, but having no dial, the first of said bars being assigned to compute only ten pence, the second being assigned to compute from two to nine pence, and the third being assigned to compute a single penny; said first bar having no rack teeth, and said second bar being driven by the first, the second bar having a rack to mesh with the pinion on the pence wheel, and said third bar having a rack in mesh with the pinion on the special computation wheel; said special wheel being provided with a carry-over train which operates every time that the special wheel is operated, said second and third racks being connected to be simultaneously brought into position to have their index-pins set by the keys.

54. The combination with a plurality of computing wheels, of actuating members individual to said computing wheels arranged to drive the same in one direction or the other for addition or subtraction, a general operator for all of said actuating members, selecting mechanism for effecting a selection of the type of drive before driving, and shifting mechanism controlled by said setting mechanism and operated by said general operator for manipulating said actuating members to one of several positions at the instant of driving.

55. The combination with a plurality of computing wheels, of a plurality of denominational members, one for each of said wheels, said denominational members each having a plurality of racks arranged to alternatively engage said wheels to drive the same, a general operator arranged to di-

rectly and positively drive all of said members, selecting mechanism for determining before hand which of said racks shall drive said computing wheels, and shifting means 5 controlled in general from said selecting mechanism and operated concomitantly with the operation of said denominational members and yet in advance thereof, to selectively move one or the other of said racks 10 into operative connections with said computing wheels.

56. The combination with an ultra-decimal computing head having a series of dial wheels at least one of which is ultra-decimal, 15 of a carry-over mechanism for said dial wheels including two separate carry-over trains to said ultra-decimal dial wheel.

57. The combination with a series of dial wheels, of a series of denominational members 20 for driving said dial wheels, a general operator for all of said denominational members to shift the same into effective driving relation with respect to said dial wheels and to directly and positively drive them 25 and thereby drive said dial wheels, and means for delaying the drive of said denominational members until said denominational members have been shifted into effective cooperation with said dial wheels.

58. The combination with a computing head including a series of computing wheels, 30 of a series of denominational members normally disconnected from said computing wheels and arranged to be connected in driving relation with said computing wheels, a general operator for all of said denominational members connected to shift the same in driving relation with said computing wheels and also connected to directly and 40 positively drive said denominational members, and a lost-motion mechanism for delaying the drive of said denominational members by said general operator until said denominational members have been connected 45 in driving relation with said computing wheels.

59. The combination with a computing head including a series of computing wheels, 50 of a series of denominational members normally disconnected from said computing wheels and arranged to be connected in driving relation with said computing wheels, a general operator connected to shift said denominational members in driving relation 55 with said computing wheels and also connected to drive said denominational members, a lost-motion mechanism for delaying the drive of said denominational members by said general operator until said denominational members have been connected 60 in driving relation with said computing wheels, and means for selecting the character of connection between said denominational members and said computing wheels.

60. The combination with a series of com-

puting wheels, of a series of actuating members for said computing wheels, said actuating members being normally disconnected from driving relation with said computing wheels, shifting mechanism for moving said 70 actuating members into driving relation with said computing wheels, a general operator for all of said actuating members to directly and positively drive the same, and interponent mechanism enabling said general operator to actuate said shifting mechanism. 75

61. The combination with a series of computing wheels, of a series of actuating members for said computing wheels, said actuating members being normally disconnected from driving relation with said computing wheels, shifting mechanism for moving said 80 actuating members into driving relation with said computing wheels, a general operator for all of said actuating members to directly and positively drive the same, 85 interponent mechanism enabling said general operator to actuate said shifting mechanism, and selecting means for determining the direction and character of shifting action of said shifting mechanism by said interponent mechanism.

62. The combination with a series of computing wheels, of a series of actuating members 90 for driving said computing wheels, said actuating members being normally out of driving relation with respect to said computing wheels, shifting means for manipulating said actuating members into driving 100 relation with said computing wheels, a general operator for all of said actuating members to directly and positively drive the same, interponent mechanism operated by 105 said general operator for actuating said shifting means, and selecting means for adjusting said interponent mechanism in one direction or the other according to the character of computation desired.

63. The combination of a series of denominational members for an ultra-decimal system of computing, said denominational members having variable numbers of pins settable thereon to determine the extent of movement thereof, and setting mechanism 110 individual to pins of the same value, certain of said denominational members and having less pins than certain others of said denominational members being provided with guards extending for a territory devoid of 115 pins to prevent the actuation of the pin-setting mechanism corresponding to said territory.

64. The combination with a series of denominational members having pins settable 120 thereon to determine the extent of movement thereof, the number of pins varying on different denominational members, of a series of setting linkages, one individual to each series of pins of the same value, means 125 130

- for concomitantly actuating one of said denominational members and one of said setting linkages, so as to set the cross selected pin, and guarding means for preventing the 5 complete concomitant action of a pin-setting linkage and a denominational member where the pin is lacking corresponding to a cross selection of such denominational member and such pin-setting linkage.
- 10 65. In a computing machine, the combination with a set of numeral keys, including the usual "1" key; of a series of computing wheels including a pence wheel; a plurality of indexing bars associated with 15 said pence wheel, one of said bars having a "10" pin thereon, and another of said bars having a "1" pin, both of said pins being settable by the said usual "1" key; and a general operator for driving both bars.
- 20 66. In a computing machine, the combination with a set of numeral keys, including the usual "1" key; of a series of computing wheels, including a pence wheel; a bar for driving said pence wheel ten steps 25 having a "10" pin thereon settable by said usual "1" key; a second bar associated with said pence wheel and having a "1" pin settable by said usual "1" key; a general operator for driving both 30 bars; and means operated by the second-named bar for computing "1" upon said pence wheel independently of the operation of that wheel by the first-named bar.
- 35 67. In a computing machine, the combination with a set of numeral keys, including the usual "1" key; of a series of computing wheels, including a pence wheel; a bar for driving said pence wheel ten steps having a "10" pin thereon settable by said 40 usual "1" key; a second bar associated with said pence wheel and having a "1" pin settable by said usual "1" key; a general operator for driving both bars forwardly and backwardly, the first-named bar being 45 arranged to compute "10" upon said pence wheel during the forward stroke of the general operator; and means operated by the second-named bar during the return stroke of said general operator for computing "1" 50 upon said pence wheel.
- 55 68. In a computing machine, the combination with a set of numeral keys, including the usual "1" key; of a series of computing wheels, including a pence wheel; a bar for driving said pence wheel ten steps having a "10" pin settable by said usual "1" key; a second bar associated with said pence wheel and having a "1" pin settable by said usual "1" key; a general operator
- for driving both bars forwardly and backwardly, the first-named bar being arranged to compute "10" upon said pence wheel during the forward stroke of the general operator; and a carry-over device operated by the second-named bar during the return stroke of said general operator for computing "1" upon said pence wheel. 60
69. The combination of three index pin bars; a pence wheel with which they are associated, the first of said bars being assigned to compute only ten pence, the second bar to compute from two to nine pence, and the third bar to compute a single penny; a general operator for the first and third bars; and coöperating means on the first 70 and second bars for driving the latter from the former.
70. The combination of an ultra-decimal computing head having a series of dial wheels, one of which is ultra-decimal; a set of numeral keys, including the usual "1" key; a series of driving bars for said wheels including a pair of bars directly associated with said ultra-decimal wheel, one bar of the pair having a "10" pin, and the other bar of the pair having a "1" pin, both pins settable by said usual "1" key; and a general operator for all of the bars. 80
71. The combination of an ultra-decimal computing head having a series of dial wheels, one of which is ultra-decimal; a set of numeral keys, including the usual "1" key; a series of bars for driving said wheels, each bar having key-set pins for determining the extent of movement of said wheels, 90 said series of bars including a pair of driving bars directly associated with said ultra-decimal wheel, one bar of the pair having a "10" pin, and the other bar of the pair having a "1" pin, both pins settable by 95 said usual "1" key; and a general operator for all of the bars. 100
72. The combination of an ultra-decimal computing head having a series of dial wheels, one of which is ultra-decimal; a set of numeral keys including the usual "1" key; and means for driving said wheels to the extents determined by the keys depressed, said driving means including devices directly controlled by the said usual "1" key for effecting a movement of said ultra-decimal wheel to an ultra-decimal extent. 105
